UNITED STATES PATENT OFFICE.

THEOPHILE DEPATIE, OF MONTREAL, QUEBEC, CANADA.

BUILDING CONSTRUCTION.

1,339,596.

Specification of Letters Patent. Patented May 11, 1920.

Application filed May 12, 1919. Serial No. 296,497.

To all whom it may concern:

Be it known that I, THEOPHILE DEPATIE, contractor, a British subject, residing at 1778 Iberville street, in the city of Montreal, in Province of Quebec, in the Dominion of Canada, have invented certain new and useful Improvements in Building Construction; and I do hereby declare that the following is a full, clear, and exact description of the same.

The present invention relates to improvements in building construction, and the main object is to provide an arrangement of interlocking bricks or blocks whereby, when they are laid up, they will form a wall particularly strong and resistant.

A further object is to provide means to lock the blocks of a wall together, particularly in walls of two blocks in thickness.

20 The invention will be understood with the aid of the accompanying drawings in which:

Figure 1 is an illustration of different designs that can be obtained with the improved brick or block shown in Figs. 2-4.

Fig. 2 is an enlarged perspective view of a block made according to the invention and used in a wall as disclosed in Fig. 1.

Fig. 3 is an enlarged perspective view 30 of one of the blocks having a Z-projection on one side and a corresponding groove on the other side thereof.

Fig. 4 is an enlarged perspective view of a corner block having an L-projection on one side thereof and a corresponding groove on the opposite side.

Fig. 5 is an enlarged perspective view of one of the binding blocks.

Fig. 6 is a perspective view of a two block 40 thickness wall, illustrating the method of applying the binding block in conjunction with the interlocking blocks.

Fig. 7 is a perspective view of a two block thickness wall illustrating another method 45 of constructing the inner side wall and binding it lengthwise.

Fig. 8 is a perspective view of a two block thickness wall illustrating another method of binding the wall lengthwise.

50 Fig. 9 is an enlarged perspective view of the type of blocks shown in Fig. 8 for binding the wall lengthwise.

Fig. 10 is an enlarged perspective view of a modified form of corner block having 55 lengthwise binding means.

Fig. 11 is an enlarged perspective view

of a modified form of block for binding lengthwise.

Fig. 12 is a perspective view of a portion of the wall constructed according to the invention, and having a semi-detached column 60 constructed with the blocks disclosed in Figs. 2 and 3.

Fig. 13 is a perspective view of a portion of a pillar constructed with the blocks 65 disclosed in Fig. 2.

Like numerals of reference indicate corresponding parts in each figure.

The block 1 illustrated in Fig. 2 has a U-shaped projection 2 on one surface thereof and on the opposite surface a corresponding U-shaped groove 3. This block 1 is adapted for instance to form the crowning block of a column as indicated in Figs. 1 and 12. The block 4 disclosed in Fig. 3, 75 which consists of a Z projection 5 on one side thereof and a corresponding groove 6 on the opposite side, is adapted to form interlocking or binding means between the said blocks 1 and also to form walls of the 80 construction disclosed in Fig. 12 of the drawings. However the blocks 4 may also be used as disclosed in Fig. 1 for ornamental purposes.

In Fig. 4 of the drawings is illustrated a 85 block 7 having on one side thereof an L shaped projection 8, and on its opposite side a corresponding L shaped groove, the said block being adapted to be used in conjunction with the blocks 1 and 4. This block 90 7 may also be used as a corner block as disclosed in Figs. 6 and 7 of the drawings.

Fig. 6 of the drawings represents a wall 95 of two block thickness having corner blocks 7 and a plurality of blocks 9 which are longitudinally disposed in relation to the walls, each of said blocks being provided on one side thereof with a central longitudinal projection 10, the opposite side of said block being provided with a groove corresponding 100 with said projection 10. Naturally when these blocks are placed over one another in the usual way, the blocks will interlock, but in order to provide bracing and locking means between the two thicknesses of blocks, a cross binding block 11 is provided and laid astride the wall as disclosed in Fig. 6, said block being provided with two projections 12 across one face thereof which are adapted to form a continuation of the projections 10 of the blocks 9, and on the opposite side of said block 11 two grooves 13

corresponding to said projections 12 are provided.

In Fig. 7 of the drawings, longitudinal binding blocks 14 of modified form are used. 5 These blocks 14 have two cross projections 15 on one side thereof, and on the opposite side is provided a central longitudinal groove 16 which is adapted to engage the projection 10 on the adjacent block 9.

10 In order to come back to the former construction, that is the block 9, a block 17 is employed having two cross grooves 18 on one side thereof, which are adapted to engage the cross projections 15 of the blocks 14, and having a longitudinal central projection 19 provided on its opposite side which is adapted to register with the projection 10 of the blocks 9.

When the blocks 14 are used, as illustrated in Fig. 7, the corner block 20 is preferably used, this block 20 having on one side thereof an L-shaped projection 21 which is adapted to register at one end thereof with the projection 10 of the block 9 and 25 having at a suitable distance from said L-shaped projection 21 a cross projection 22. On the opposite side of said block corresponding to said projection 21 is an L groove 23, and a cross groove 24 corresponding to 30 said projection 22.

Should it be found convenient to use the blocks 9 above the said blocks 14 the blocks 17 are first placed over the blocks 14, and the corner block 7 will be arranged on top 35 of said block 20.

It will readily be seen from the foregoing description that a two-block thickness wall can be easily braced by employing this means of construction and that each layer 40 of bricks or blocks can be bound together to form a most solid construction.

No claim is herein made for the blocks 9 as these blocks have been used for years, but the object of this invention is principally to 45 provide a binding block which, when used in conjunction with the blocks 9, will brace the wall longitudinally and laterally.

What I claim as my invention is:

A wall comprising a plurality of superposed layers of horizontally-laid blocks or 50 bricks arranged longitudinally of the wall and having their top and bottom faces formed with mating locking ribs and grooves located centrally and longitudinally thereof, the ribs and grooves on the 55 contacting faces of superposed bricks interfitting with one another to brace the wall longitudinally; a plurality of cross-bricks disposed transversely of the wall in certain of the layers with their opposite sides faces 60 abutting against the ends of the adjacent longitudinal bricks in said layer or layers; the cross-bricks being provided upon their top and bottom faces with mating cross-ribs and cross-grooves which interlock, re- 65 spectively, with the longitudinal grooves and ribs on the longitudinal bricks directly above and below them to brace the wall laterally and which respectively aline with the longitudinal grooves and ribs on the 70 abutting longitudinal bricks in the same layer or layers to form continuations thereof; and a plurality of longitudinal bricks included in certain of said layers and having on one face at least one transversely- 75 disposed locking element and on the opposite face a longitudinal locking element to interfit with the longitudinal interlocking elements and cross-interlocking elements on the first-named longitudinal bricks and on 80 the cross-bricks, the locking element on one face of each second-named longitudinal brick being in the form of a rib or projection, and that on the opposite face being in the form of a groove; substantially as de- 85 scribed.

Signed at Montreal, Quebec, Canada, this 16th day of April, 1919.

THEOPHILE DEPATIE.
